UNITED STATES PATENT OFFICE.

JOHN F. O'MALLEY, OF GENEVA, NEW YORK.

DIRECTION-SIGNAL FOR VEHICLES.

1,276,563.

Specification of Letters Patent. Patented Aug. 20, 1918.

Application filed May 8, 1917. Serial No. 167,238.

To all whom it may concern:

Be it known that I, JOHN F. O'MALLEY, a citizen of the United States, residing at Geneva, in the county of Ontario and State 5 of New York, have invented certain new and useful Improvements in Direction-Signals for Vehicles, of which the following is a specification.

This invention relates to signal devices, 10 particularly to signal devices for vehicles and has for its object the provision of a novel form of signal adapted to be secured upon the front and also the rear of a motor vehicle in order that the driver may indicate 15 to following and approaching vehicles and also traffic officers an intended change in direction or a stop.

An important object is the provision of a 20 device of this character which is electromagnetically operated, and controlled by a switch located upon or near the steering column within convenient reach of the driver.

Another object is the provision of a signal 25 device so constructed that when set to indicate an intended change in direction it will remain fixed until the control switch is moved by the operator, thus avoiding the necessity of manually holding any movable parts stationary to maintain the signal at the 30 proper indication.

An additional object is the provision of a device of this character embodying an incandescent lamp to render the signal visible at night, the control switch and electric circuit 35 being so arranged that the lamp does not become lighted until the control switch is moved to indicate a change in direction, the advantage being that the sudden illumination of the signal dial will attract attention in becoming suddenly conspicuous.

Further objects and advantages such as compactness, comparative cheapness and general efficiency will become apparent during the course of the following specification 45 taken in conjunction with the drawings, in which:

Figure 1 is a conventional side elevation of an automobile, showing my signal applied to the front and rear thereof,

Fig. 2 is a face view of the signal,

Fig. 3 is a view taken through the casing back of the dial,

Fig. 4 is a vertical sectional view,

Fig. 5 is a plan view of the control switch, and

55

Fig. 6 is a diagrammatic view of the electric circuit.

Referring more particularly to the drawings, the numeral 1 designates my signal device as a whole, supported upon suitable 60 brackets 2 at the front and rear of an automobile, at any convenient or suitable location, as shown in Fig. 1. As the front and rear devices are identical, a detailed description of one will suffice to bring out the invention 65 fully.

The device comprises a casing 3, preferably of cylindrical shape and of any desired material, having a shoulder 4 at its outer edge to serve as an abutment for a dial 5 70 formed of white, translucent glass, and also having a flange 6 for the retention of a transparent glass cover 7 spaced from the dial 5 by suitable packing 8. The well known type of locking rim 9 is engaged 75 upon the edge of the casing to retain the glass cover 7 in place.

A shaft 10 is journaled centrally of the casing and carries at its outer end an indicator or pointer 11 preferably in the shape 80 of an arrow, formed of light-weight material and painted a dark color to be conspicuous in front of the dial. Adjacent the rear wall of the casing the shaft also carries a pinion 12.

In order that the arrow 11 may be moved to point to different legends, "S" meaning "stop," "L" meaning "left" and "R" meaning "right," provided at the bottom and sides of the dial, respectively, I provide a 90 shaft 13 journaled within a frame 14 secured upon and insulated from the back wall of the casing. This shaft carries a gear 15 meshing with the pinion 12 on the arrow shaft 10. A pin 16 projects from the 95 gear 15 and has secured thereto a spring 17 which has its other end fastened to a post or eye 18. This spring normally holds the gear in such a position that the arrow 11 points downwardly, indicating no intended 100 change in the direction of the vehicle, and also returns the arrow to this position after a signal has been given and a change completed.

In order that the gear 15 may be moved 105 to actuate the arrow, I provide electro-mag-

2

nets 19, 20 and 21 mounted in suitable brackets 22 secured upon the back wall of the casing. The magnets have associated therewith armatures 23, 24 and 25 respectively which are flexibly connected with the brackets 22 by springs 26. Pivotally connected with the armature 23 at the point 27 is a rod 28 which has its other end slidably connected with a pin 29 projecting from the gear 15. The armature 24 has pivotally connected therewith at the point 30 a rod 31 which has its other end slidably connected with the pin 29 also. Similarly, the armature 25 has pivotally secured thereto at the point 32 a rod 33 which has its other end slidably connected with the pin 16. The slidable connections are to prevent retrograde movement of the other armatures when any one armature is actuated.

20 A contact 34 of suitable material is disposed within the casing and is supported by a post 35 from which it is insulated. A movable contact 36 is secured to the gear 15 and is in constant contact with the member 34, over which it travels as the gear 15 is rotated. An incandescent lamp 37 is provided and secured within a socket 38 at the top portion of the casing.

The control switch 39, located upon or near the steering column as found most convenient, comprises a switch arm 40 adapted to be moved into engagement with any one of a plurality of contact buttons 41, 42 and 43, which are disposed at the right, bottom 35 and left, respectively, of the switch body, corresponding to intended changes in direction of the vehicle. The switch further comprises an arm 44 adapted to be moved into engagement with a contact button 45 for controlling the energization of the incandescent lamps 37.

The electric circuit is as follows: The source of current 46 which may be dry cells or the storage battery commonly provided upon modern motor vehicles is connected with the switch arm 40 by a wire 47. The contact button 41 is connected with the magnets 21 in the casings at the front and rear of the vehicle by a wire 48. The button 42 is connected with the magnets 19 by a wire 49, and the contact button 43 is connected with the magnets 20 by a wire 50. A wire 51 is connected to one terminal of one of the lamps 37 and has its other end connected 55 with a terminal of the other lamp, a wire 52 being connected with the wire 51 and returning to the source of current 46. The magnets 19, 20 and 21 are connected with the wire 51. The contacts 34 are connected with each other by a wire 53 which is also connected with the switch arm 44 by a wire 54. The frames 14, and consequently the contacts 36 are connected with the other terminals of the lamps 37 by wires 55. The

button 45 is connected with the wire 53 by a wire 56.

The operation of the device is as follows:

Assuming that the driver wishes to turn to the right, he will grasp the switch arm 40 and move it into contact with the button 41, whereupon current will flow from the source 46, to the arm 40, button 41, through the wire 48, magnets 21, and back to the source of current through the wires 51 and 52. This energization of the magnets 21 will cause the armatures 25 to be attracted toward the cores of the magnets, pulling upon the rods 33 and rotating the gears 15 through a small arc, this movement being amplified and transmitted to the arrow shafts by the pinions 12. The arrows will then be rotated through an arc of ninety degrees, pointing to the legends, "R". The arrows will remain in this position until the switch arm 40 is disengaged from the button 41. If it is desired to turn to the left, the switch arm 40 will be moved into the contact with the button 43, whereupon current will flow from the source 46, through the arm 40, button 43, wire 50, magnets 20, and back to the source through the wires 51 and 52. This energization of the magnets 20 will cause the armatures 24 to be attracted toward the magnet cores, pulling upon the rods 31 and rotating the gears 15 through a small arc. This movement is amplified and transmitted to the shafts 10 and arrows 11 through the pinion 12, causing the arrows to be rotated to the left through an arc of ninety degrees and to point to the legend "L."

If it is desired to signal an intention to stop, the driver will move the switch arm 40 into contact with the button 42, whereupon current will flow from the source 46, through the wire 47, arm 40, button 42, wire 49, through the magnets 19 and back to the source through the wires 51 and 52. The consequent energization of the magnets 19 will cause the armatures 23 to be attracted, resulting in a partial rotation of the gears 15 through the medium of the rods 28. As these armatures 23 have twice the play of the other armatures, the gears 15 will be moved through such an arc that the arrows will be swung through an arc of one hundred and eighty degrees, pointing straight upward to the legend "S."

When the signal is used at night, the switch arm 44 is moved into engagement with the contact button 45. This will not result in lighting the lamps 37 until the switch arm 40 is engaged with either of its associated contact buttons. When the switch arm 40 is then contacted with any one of the buttons 41, 42 or 43, the current after passing through the associated magnets will divide, a portion returning through the wires 51 and 52 to the source, and the remainder

passing through the lamps 37, wires 55, frames 14, contacts 36, contacts 34, wires 53, wires 54, switch arm 44, contact button 45, wires 56, and wire 52 back to the source, it 5 being of course understood that resistance commensurate with the resistance of the lamps must be interposed in the wire 52 between the wires 51 and 54. This will result in energization of the lamps simultaneously 10 with the giving of the signal.

From the foregoing description and a study of the drawings, it will be apparent that I have thus provided a comparatively simple, compact, responsive and highly efficient signal for motor vehicles, which will 15 be effective in promoting safety even in crowded traffic.

It will be readily understood that I do not wish to limit myself to the exact specific 20 details of construction shown and described, as I reserve the right to make such changes in the form, construction and arrangement of parts as will come within the scope of the subjoined claims.

Having thus described my invention, I 25 claim:

1. A device of the character described, comprising a casing, a member revolvably mounted therein, an indicator movable with 30 said member, a plurality of electro-magnets in said casing, swinging armatures individually associated with said magnets, and means connected individually with said armatures and different points at the periphery of said member and a control switch, 35 said magnets and said switch being included in a circuit including a source of current.

2. A device of the character described, comprising a casing, a shaft journaled there- 40 in, an indicator secured on said shaft, a pinion on said shaft, a gear meshing with said pinion, a plurality of electro-magnets in said casing, swinging armatures adapted to be acted upon by said magnets, rods con- 45 nected with said armatures and connected with said gear at different points adjacent the periphery thereof, a switch arm, and a plurality of contact buttons engageable by said arm, said magnets, arm and contact 50 buttons being included in a circuit including a source of current.

3. A device of the character described, comprising a casing, a dial therein, a shaft revolvable in said casing, an indicator on said 55 shaft traveling over said dial, and means for turning said shaft to rotate said indi-

cator through selected arcs comprising an electro magnet for each arc, means for energizing said magnets, an armature associated with each magnet and adapted to be moved thereby, a rod connected with each armature, a gear connected with said shaft, pins extending from said gear and engaged by said rods, a switch arm, and a plurality of contact buttons corresponding to the number of magnets, said magnets, switch arm and contact buttons being included in a circuit including a source of current.

4. A device of the character described, comprising a casing, a dial therein, a shaft 70 journaled in said casing, an indicator secured upon said shaft and adapted to travel over said dial, a pinion on said shaft, a second shaft journaled in said casing, a gear on said second shaft meshing with said pinion, pins extending from said gear, and means for moving said indicator through selected arcs over said dial comprising an electro-magnet for each arc, armatures associated with said magnets and adapted to be 75 moved thereby, rods pivotally connected with said armatures and slidably connected with said pins, a switch arm, and a plurality of contact buttons corresponding in number to the magnets and adapted to be engaged by said switch arm, said magnets, switch arm and contact buttons being included in a circuit including a source of current.

5. A device of the character described, comprising a casing, a shaft revolvable in 90 said casing, an indicator on said shaft adapted to be moved through selected arcs, electro-magnets in said casing corresponding in number to the number of arcs, armatures associated with said magnets, a second 95 shaft journaled in said casing, a gear on said second named shaft, a pinion on said first named shaft meshing with said gear, members pivotally connected with said armatures and individually pivotally connected to the periphery of said gear, a switch arm and a plurality of contact buttons associated with said magnets, an incandescent lamp in said casing, and a second switch arm and contact button associated with said lamp, 100 said lamp, said switch arms and contact buttons, and said magnets being included in a circuit together with a source of current.

In testimony whereof I hereto affix my signature.

JOHN F. O'MALLEY.
